UNITED STATES PATENT OFFICE.

JOHN FRANCIS O'MALLEY, OF AVOCA, PENNSYLVANIA.

MATCH-HOLDER.

1,114,509.

Specification of Letters Patent. Patented Oct. 20, 1914.

Application filed November 21, 1913. Serial No. 802,234.

To all whom it may concern:

Be it known that I, JOHN FRANCIS O'MALLEY, a citizen of the United States, and a resident of Avoca, in the county of 5 Luzerne and State of Pennsylvania, have invented a new and Improved Match-Holder, of which the following is a full, clear, and exact description.

The invention relates to match holders, 10 such as shown and described in Letters Patent of the United States, No. 1,066,311, granted to me July 1, 1913.

The object of the present invention is to provide a new and improved match holder, 15 which is exceedingly simple and durable in construction and more especially designed for holding a bunch of paper or wooden matches, and arranged to allow of conveniently fastening the bunch of matches in 20 place and allow ready removal of a match whenever desired.

In order to accomplish the desired result use is made of a stand provided with an opening, and a pocket leading into said 25 opening, the said pocket being adapted to receive the stub of a bunch of matches with the matches extending permanently into the said opening, and means held on the stand for removably securing the stub in place in 30 the said pocket.

A practical embodiment of the invention is represented in the accompanying drawings forming a part of this specification, in which similar characters of reference indicate corresponding parts in all the views.

Figure 1 is a perspective view of the match holder; Fig. 2 is a sectional side elevation of the same; and Fig. 3 is a transverse section of the same.

From a suitably constructed base A rises an upright B provided with an opening C and with a pocket D leading into the said opening C at the upper end thereof, as will be readily understood by reference to the 45 drawings. The pocket D is adapted to receive the stub E' of a bunch of matches E with the matches extending in the opening C. As shown in the drawings, the bunch of matches E is of well known construction being 50 preferably composed of a plurality of layers of matches extending from the stubs E' fastened together by a suitable fastening

device E², which in this case also forms an eyelet or a reinforced opening E³ for the passage of a transverse pin F held removably in a hole G extending from the front of the stand B to the rear thereof and leading into the pocket D. It will be noticed that the stub E' of the bunch of matches fits snugly into the correspondingly-shaped 60 pocket D and the stub E' is removably secured therein so that the matches E are displayed within the opening C. The opening C is preferably of a height in excess of the length of the matches so that any one 65 of the matches can be readily broken off from the stub E' whenever it is desired to use one of the said matches. In case all the matches E have been removed from the stub E' then the pin F is pushed out of its 70 hole G by the use of a suitable tool H under the control of the operator and having a reduced end H' adapted to engage one end of the pin F to push the same out of the hole G. When the pin F has been removed 75 and the tool H has been withdrawn then the stub E' readily drops out of the pocket D and a new bunch of matches can be attached to the stand by placing the stub E' into a pocket D and securing the stub therein by 80 reinserting the pin F in the hole G.

The base A of the stand is provided with an opening A' through which appears a scratching surface I held in place on the under side of the base A by a plate J removably fastened to the base by screws K, as plainly indicated in Figs. 2 and 3. On loosening the screws K the scratching surface I if worn out can be readily removed and replaced by a new one.

The match holder shown and described is very simple and durable in construction and composed of few parts not liable easily to get out of order.

Having thus described my invention, I claim as new and desire to secure by Letters Patent:

A match holder, comprising a stand provided with a transverse opening extending to within a short distance of its upper end, 100 a pocket in its upper end above the opening and leading into the said opening, said pocket being of a depth approximately equal to the width of the stub of a bunch of

matches, and a transverse hole extending through its upper end, and a pin in the hole of the stand and adapted to engage the stub of a bunch of matches to hold it in the said pocket with the matches extending permanently into the opening of the stand.

In testimony whereof I have signed my

name to this specification in the presence of two subscribing witnesses.

JOHN FRANCIS O'MALLEY.
